George J. Webster

ATTORNEY

UNITED STATES PATENT OFFICE.

THOMAS E. MARCHAND, OF SACRAMENTO, CALIFORNIA.

PENCIL-HOLDING CLIP.

Application filed August 5, 1922. Serial No. 579,880.

To all whom it may concern:

Be it known that I, THOMAS E. MARCHAND, a citizen of the United States, residing at Sacramento, county of Sacramento, 5 State of California, have invented certain new and useful Improvements in Pencil-Holding Clips; and I do declare the following to be a full, clear, and exact description of the same, reference being had to the accompanying drawings, and to the characters of reference marked thereon, which form a part of this application.

This invention relates to improvements in clips for holding pencils, pens and the like, 15 the principal object being to provide a device of this character in the form of a small one-piece member adapted to be removably mounted on the index finger of the writing hand of the user of the pencil, 20 and provided with means for frictionally holding a pencil so positioned that the user may, with the hand already holding and using the pencil, engage the pencil with the clip, and likewise disengage the pencil 25 when it is again necessary to use the same.

A further object is to provide a clip device to hold a pencil in such a manner that the latter is then out of the way, and the user or wearer of the clip may have the 30 free and full use of his hand for any purpose he may desire.

This device is especially intended for use by bookkeepers, accountants and those engaged in clerical work generally.

Such workers, while using pencils or pens 35 more or less continuously, frequently have to stop writing to answer the telephone, run an adding machine or similar device, and to do tasks of a similar nature in which the 40 hands must be free.

The pencil in such cases is usually placed either behind one ear, from where it is liable 45 to drop and break the point, or it is laid on the desk to become mislaid among the sun-dry loose books and papers on the desk. The use of my device eliminates these inconveniences, with their attendant loss of time.

A further object of the invention is to 50 produce a simple and inexpensive device and yet one which will be exceedingly effective for the purposes for which it is designed.

These objects I accomplish by means of 55 such structure and relative arrangement of

parts as will fully appear by a perusal of the following specification and claims.

In the drawings similar characters of reference indicate corresponding parts in the several views:

Fig. 1 is a fanciful view of a human hand manipulating a pencil, showing the clip as installed.

Fig. 2 is a similar view, showing the pencil held by the clip.

Fig. 3 is a detached perspective view of the clip.

Referring now more particularly to the characters of reference on the drawings, the numeral 1 denotes a curved band, preferably of spring-metal, adapted to fit onto the index finger 2 of the hand of the user and to be positioned on the finger between the hand and the nearest knuckle, as shown.

The portion 1 is substantially U-shaped, 75 thus leaving an opening 3 between the sides through which the finger is pressed.

Formed with the band 1 and overhanging the opening 3 somewhat is another and smaller U-shaped member 4, the medial line 80 of which is substantially at right angles to the medial line of the portion 1, while said portions extend in parallel planes.

The opening of the portion 4 projects outwardly of that side of the band 1 to which 85 it is connected, or away from the opening 2.

The portion 4 forms the clip, and is of a size, from side to side, to receive and frictionally engage and hold a pencil 5 of the usual diameter, the outer or free edge of 90 said clip portion being bent or curved away from its opening somewhat as at 6, to better guide the pencil into place.

The free end of the band 1 is also similarly bent out as shown at 7, so that there 95 is no likelihood of that end of the band cutting into the flesh of the finger.

In operation, the device is positioned as shown in Fig. 1, with the opening of the clip facing toward the pencil as held and 100 the medial line of the clip being substantially horizontal when the hand is held in a normal writing position.

This enables the pencil to be engaged with the clip by merely rolling the pencil along 105 the face of the index finger nearest the thumb into engagement with the clip by means of said thumb, a slight pressure of the thumb being sufficient to push the pencil firmly into the clip. The finger encircling 110

the band will not slip around the finger owing to the frictional engagement had with the use of said spring material.

To engage the pencil from the clip, the thumb is manipulated so as to cause the tip thereof to engage the pencil on the side thereof opposite the clip opening, and on the side of the clip nearest the hand. If a slight pressure is then exerted to withdraw 10 the pencil from the clip, the pencil may then be easily moved into the writing position without the aid of the other hand.

Of course if desired, the clip may be mounted on a finger of the other hand, in 13 which case a pencil may be easily engaged with the clip without any practice being necessary.

From the foregoing description it will be readily seen that I have produced such a 20 device as substantially fulfills the objects of the invention as set forth herein.

While this specification sets forth in detail the present and preferred construction of the device, still in practice such deviations from such detail may be resorted to as

do not form a departure from the spirit of the invention, as defined by the appended claims.

Having thus described my invention, what I claim as new and useful and desire to secure by Letters Patent is:

1. A pencil holding device comprising a spring band adapted to frictionally fit onto a finger of a hand, and a spring clip extending outwardly of the band and whose axis is substantially parallel to that of said band; said clip having a side opening through which the pencil is inserted.

2. A pencil holding clip comprising a substantially U-shaped band adapted to be frictionally pressed onto a finger of a hand, and a U-shaped clip formed with said band, and adapted to frictionally engage a pencil, the opening of the clip facing outwardly of the band and the medial lines of the clip and band being substantially at right angles to each other.

In testimony whereof I affix my signature.

THOMAS E. MARCHAND.
